BALL-LAPPING MACHINE.

1,419,078.

Specification of Letters Patent. Patented June 6, 1922.

Application filed March 19, 1919. Serial No. 283,622.

To all whom it may concern:

Be it known that I, ALBERT F. ROCKWELL, a citizen of the United States, residing at Bristol, in the county of Hartford and State 5 of Connecticut, have invented certain new and useful Improvements in Ball-Lapping Machines, of which the following is a specification.

This invention relates to ball-lapping devices for use in the manufacture of ball-bearings, and provides an apparatus in which a greatly increased production, efficiency of operation, and improved quality of product is obtained over results possible to 10 be secured by devices of this general nature known and used in the prior art.

In the art of manufacturing ball elements for bearing constructions it has heretofore been the practice to reduce the ball to their 20 final spherical form either by a grinding or a lapping operation, in which the balls have been caused to repeatedly traverse one or more annular grooves by the contact therewith of a rotating grinding or lapping member, the repetition of the travel of the balls 25 over and over again through the same grooves being continued until they were reduced to the required size. Upon a careful analysis, it will be clear that in a construction such as this, in which the balls must 30 pass more than once through the same groove, the individual grooves will be repeatedly traversed by balls of diminishing size. This is objectionable in general 35 for the reason that the best grinding conditions are attained only when there is a definite and constant size relation existing between the grooves in the lapping members and the balls undergoing the lapping 40 operation, and such conditions cannot be had when the same balls are caused to travel repeatedly through the same grooves a great 45 number of times, as has heretofore been the practice.

With the end in view of providing a lapping machine in which each one of the lapping grooves acts on approximately only the same size of balls, as against the previously-known methods of ball production in which 50 repeated operations were performed by the same grooves on balls differing in size, as a result of their traveling over and over again through the same groove, I have succeeded in producing an apparatus in which 55 a bank or series of sets of lapping plates

is provided, and I preferably provide a sufficient number of the lapping-device units to obviate the necessity for causing the balls to travel through the grooves more than once, thereby establishing a definite and constant size relation between the grooves and the balls passing therethrough, whereby the most efficient operating conditions are attained. However, I do not hold myself rigidly to this particular mode of operation, 60 but may repeat the travel of the balls through the grooves under certain circumstances, without departing from the spirit of my invention, although I do not consider this to be the most desirable practice. 65 In order to carry out my invention, I preferably form the successive series of lapping grooves either in a gradually decreasing size or in condition to readily assume such size in use so as to conform with the minute 70 changes in size that the balls undergo in passing from groove to groove in their travel from the entrance to the exit end of the machine, and I provide structure whereby the form of all the grooves will be of substantially the same radius of curvature as 75 that of the balls passing therethrough, to thereby apply the grinding action simultaneously to substantially every portion of the spherical surface of the balls. 80

I not only provide a bank or series of sets of lapping plates, but, I also contemplate the making of changes in the number of lapping sets or units employed in any given operation, in accordance with the particular 90 requirements of different classes of work. This flexibility in the capacity of the machine by which it may be adapted to operate on a batch of ball members requiring a comparatively small amount of lapping action, or by which the number of lapping units employed can be extended to 95 suit the requirements of a batch in need of a more extended operation, is a useful and important feature of the invention. 100

To provide for the application of a sufficient pressure on the balls as well as to still further insure that substantially the entire surface of the balls will be acted upon, I provide for the actual contact with each 105 other in operation of the oppositely-disposed groove-separating ribs or partitions of the contiguous faces of adjoining plates, and form the contacting faces of these ribs with a properly proportioned area and 110

width to cause them to be worn down at a somewhat faster rate than the rate of wear of the grooves, to thereby insure at all times the maintenance of an adequate degree of pressure between the lapping grooves and the engaged surfaces of the balls.

Another feature of the invention resides in the mounting of the ball-lapping plates in a vat or trough-shaped container in such a manner that a portion of each plate at all times is immersed and rotates in an abrasive mixture such as emery and oil. By this arrangement, I have succeeded in providing a device in which the abrasive material is constantly stirred while the machine is in operation without the use of supplementary stirring apparatus, such as is used in prior devices, and, in addition, an extremely regular and uniform application of the abrasive material to the lapping grooves is effected, in contrast to the irregular application which was secured in prior devices with a resulting lack of uniformity and efficiency in the lapping operation.

Still another feature of the invention resides in a simple and effective form of transfer mechanism which I have provided for transferring the balls successively from one groove to another, and preferably from one face to the other of the stationary plates in alternation, at the completion of travel of the balls through each successive groove. I also provide means for automatically transferring the balls from one set of lapping members to the next to thereby cause the balls to traverse in turn the entire series of sets of lapping members contained in the machine.

Means are also provided for exerting a substantial lateral pressure on the plates in order to hold them in the most effective operating relation to the interposed balls and to do this without exerting an objectionable end thrust on the shaft. I accomplish this by causing the thrust forces acting longitudinally of the drive-shaft to be mutually balanced and self-contained between the ends of the shaft, so that no end thrust is exerted on the shaft bearings and consequently no thrust bearing for the shaft is required. This has been accomplished by mounting both the stationary and the rotatable plates on the shaft in such a way that they are movable along the shaft and confined, together with a powerful spring which is used to hold the plates in close contact, between suitable collars mounted on the shaft, one of which has a fixed relation thereto, and the other of which has an adjustable relation therewith.

In general, it is the object of the invention to provide an apparatus for performing the lapping operation on the balls in a continuous operation that not only secures a greatly increased production of finished balls over

the production secured by lapping machines known and used in the prior art, but also turns out a more regular and uniform product and saves wear upon the lapping machine in several important respects.

In the drawings in which a preferred embodiment of the inventions is illustrated,

Fig. 1 is a vertical, longitudinal section of a ball-lapping machine embodying the invention;

Fig. 2 is an end elevation of the machine shown in Fig. 1 looking from the left;

Fig. 3 is a face view of one of the stationary lapping members;

Fig. 4 is an edge view of a portion of the lapping plate shown in Fig. 3;

Fig. 5 is an enlarged view of a portion of a ball transfer member forming part of the transfer mechanism shown in Figs. 3 and 4;

Fig. 6 is a diagrammatic view on an enlarged scale of a detail of a ball-transfer device used in the machine; and

Fig. 7 is a diagrammatic view showing the course of travel of the balls in the lapping and transfer operations.

In the drawings, I have shown a ball-lapping machine in which a bank or series of alternately-arranged stationary lapping plates 1 and 2, and rotatable lapping plates 3 and 4, are mounted on the horizontal main drive-shaft 5 which is journaled in bearings 6 and 7 on the end plates 8 of the vat or trough-shaped framework of the machine and is provided with suitable fixed and loose drive pulleys 17 and 18. The contiguous faces of the lapping discs or plates are provided with a series of concentric grooves 9 in their faces through which the balls being operated upon are caused to travel by the rotation of the rotatable plates. In the operation of the device, means are provided for transferring the balls at the completion of the travel about the annular path afforded by any given groove on one face of a fixed plate through the plate to the oppositely-disposed groove on the opposite face thereof, and for re-transferring the balls through the plate when their travel through the latter groove is completed, and at the same time for shifting them radially outward to the next pair of concentric grooves in the series. This operation of causing the balls to travel in succession through each pair of oppositely-disposed grooves is continued until all the grooves from the innermost to the outermost groove in any given set of lapping plates has been traversed, when the balls are automatically transferred to a new series of grooves occupying the contiguous faces of the next set of plates, when a similar course of action is proceeded with, and a repetition of the operation described,—that is, the progressive working of the balls outwardly through each oppositely disposed pair of grooves from the innermost to the outermost

grooves in the series,—is continued until the balls have traversed the entire series of grooves in the apparatus and have emerged from the exit end of the final groove with 5 the lapping operation completed. The balls are initially and continuously fed into one end of the machine from a hopper 10, and a corresponding number of finished balls is continuously delivered at the other, so that 10 there is no necessary interruption or stoppage of the machine, under normal operating conditions, while a supply of balls is available in the hopper.

In order to initiate the travel of the balls 15 into the apparatus to undergo the lapping operation, the hopper 10 is arranged to be rotated, and for this purpose the hopper is provided with a vertical drive shaft 11 journaled in a bearing 12 mounted on the hopper 20 supporting base member 13. The hopper drive-shaft 11 is preferably driven through a gear connection with the counter-shaft 14 which carries a pulley 15 from which a belt-driving connection may be had with a pulley 25 16 carried by the corresponding end of the main drive-shaft 5. It will be seen that the agitation of the balls brought about by the rotation of the hopper 10 will insure the feeding of a continuous succession of balls 30 into the stretch of flexible metallic tubing 19, which leads to the first fixed plate-carrying discs 20 in the series of sets of lapping devices.

For the purpose of producing relative 35 rotation between contiguous lapping plates, the stationary plate-carrying discs 20 are constructed with central openings 21 within which the drive-shaft 5 can freely turn, and, to prevent rotation of the discs 20, 40 each one of them is provided with a stop member taking the form of a bolt 22 which is fitted into a notch 23 in the periphery of the disc and which bears against the upper edge of the framework of the machine, thus 45 holding the disc and the grooved plates 1 and 2 carried thereby against rotation. The rotatable plate-supporting members or discs 24 and 25 which alternate with the stationary discs 20, instead of being constructed to 50 permit of the free rotation of the discs, are provided with key members 26 which engage with a groove 27 extending longitudinally of the shaft. It will be seen that by the construction described the plate-carrying members 24 and 25 are caused to rotate with the 55 drive-shaft 5, and that both the rotatable plate-carrying members 24 and 25 and the stationary plate-carrying discs 20 are capable of movement longitudinally of the shaft, a 60 feature which is utilized in bringing about and maintaining an effective operating pressure on the balls interposed between the plates, as will be hereinafter described.

After passing through the feeding tube 19 65 from the hopper 10, the balls are directed by

means of a passage 62, located in the first stationary plate-supporting disc 20, to a suitable transferring device by means of which the balls are transferred alternately from one face to the other of the stationary lapping member, and in succession from the innermost to the outermost of the series of lapping grooves 9 in the set. Upon emerging from the final groove, the balls are directed by means of another flexible feeding tube, 70 such as is shown at 28, to the passage corresponding to 62 in the stationary plate-supporting disc 20 of the second set, whereupon the balls traverse in turn all the lapping grooves of that set from the innermost to 80 the outermost grooves, and are then transferred to the next set of lapping members, and so on. It will be seen that by this general construction the balls traverse in succession all of the lapping grooves in the entire 85 series, and that no one ball passes through any one lapping groove more than once under ordinary conditions.

The construction of the transfer mechanism is shown generally in Figs. 3, 4, and 5 90 of the drawings and in a diagrammatic arrangement in Figs. 6 and 7. This construction includes the transfer plates 29 and 30, which may be attached to the opposite faces of the disc 20 in any preferred manner, and 95 an intermediate transfer member 50 having the plate members 51 provided with perforations 52 which have a supporting engagement with the ends of the flexible metallic ball-conveying tubes 53. The plates 29 100 and 30 are provided with series of obliquely-arranged passages through which the balls are transferred from the grooves on one face of the lapping member through the corresponding passages of the intermediate transfer member 105 and to the corresponding oppositely-disposed grooves on the other face, and then to the next outer grooves on the first-mentioned face, and so on to the feed-tube 28. I preferably cause the balls to traverse each pair of oppositely-disposed 110 grooves in succession from the innermost to the outermost pair of grooves in the series, and I have achieved this in the manner most clearly indicated in the diagrammatic views 115 constituting Figs. 6 and 7 of the drawings.

In operation, as the balls are fed into any given lapping device through the passage 62 to the transfer member 50, they are diverted through a wall of the transfer member 120 50 to the entrance end 31 of a passage in the transfer plate 29 leading to groove member 1 which is the innermost of the series of concentric grooves on the corresponding side of the stationary lapping member. The 125 course of the balls is now through the groove 1, indicated mainly by dotted lines in Fig. 6, until an outlet passage through the plate 29 is reached having an exit 32 from which the balls are conveyed through passage 33 130

across the space, greatly exaggerated and distorted in Fig. 6 for the sake of clearness, to the entrance end 34 of a passage leading through transfer plate 30 to the other face 5 of the lapping member and to groove member 1 in that plate, oppositely disposed with relation to the first groove referred to. This groove having been traversed, the balls emerge at 35 and enter the passage 36 10 through which they pass to the other transfer plate 29, but it is to be noted that in the passage of the balls from plate 30 to plate 29,—that is, from the right hand to the left-hand face of the lapping member,—the balls 15 do not pass to the oppositely-disposed groove member 1, which has already been traversed, but instead travel to the entrance 37 of a passage leading to the second or next outer groove on the plate 29. Having traversed 20 groove number 2, in turn, the balls emerge at 38 and travel through passage 39 to the entrance 40 of the oppositely-disposed groove number 2 on plate 30. When this groove has been traversed, the balls emerge 25 at 41 and travel through passage 42 to groove number 3 of plate 29.

Thus, it will be seen that the balls pass in alternation from one to the other side of the fixed lapping member and that, in passing 30 in one direction through the transfer plates the balls invariably move from one to the oppositely-disposed member of a pair of grooves; and that in passing through the transfer plates in the opposite direction, 35 the balls invariably move outwardly to the first groove of the next outer pair. This operation is continued, as has already been indicated, until each successive concentric pair of grooves from the innermost to the 40 outermost has been traversed.

In order to prevent the production of an end thrust in the main drive-shaft 5, and thus eliminate the need for making use of thrust bearings, I preferably mount the series 45 of lapping members between a thrust collar 43, rigidly secured to the main drive-shaft 5, and a pressure-regulating nut or follower 44 having threaded engagement with the threaded portion 45 of the drive-shaft 5. 50 It will be seen that, by turning the follower 44, any required degree of lateral pressure can be applied to the lapping members through the spring 46, and that the pressure thus produced is offset by the thrust collar 43, with the result that the end thrust forces exerted on the drive-shaft 5 are mutually balanced and that no end thrust is exerted on the shaft bearings by the drive-shaft as a whole. The freedom which the 55 lapping members have of movement along the shaft 5 permit of their being forced into any desired compressing engagement with the interposed balls in the grooves 9.

In order to bring about the most effective 60 engagement of the lapping grooves with the

balls, I preferably form the grooves on substantially the same or on a slightly larger radius of curvature than that of the balls themselves, so that the entire surface of the balls is acted upon by the attritious material 70 carried in the opposing grooves. I preferably still further increase the effective area that is acted upon by the lapping grooves by cutting the grooves in each plate to such a depth that the ribs or partitions separating adjacent grooves make contact with the opposing ribs on the contiguous plate. I have discovered that, by properly proportioning the width of the contacting faces 75 of the ribs, they will be worn down somewhat more freely than the corresponding rate of wear of the lapping grooves, so as to insure that the balls and coacting groove surfaces will be subjected to a suitable operating pressure. This provision for a 80 faster rate of wear on the faces of the partitions than on the ball-engaging surfaces of the grooves not only has the additional useful function of providing for the ready access of the abrasive-charged liquid to the 85 lapping grooves and the balls undergoing the lapping operation therein, but it also avoids the need for occasionally removing and refacing the plates, as would otherwise be necessary. 90

In order to apply the abrasive agent in a regular and effective manner, I have provided a vat or trough, as at 47, in which a supply of lapping material 48, such as emery and oil, can be placed, and into which the lower portions of the lapping members extend. It will be very clear that, by this arrangement, I not only provide for a continual desirable agitation and stirring of the material 48 by the rotation of the rotatable lapping members therein, but a very regular and uniform application of the liquid to the various lapping grooves is effected. 100

Because of the desirability of relieving the main drive-shaft 5 of the entire weight 110 of the lapping members, as well as to prevent wear on the shaft, I preferably form the stationary plate-carrying discs 20 with a greater diameter than that of the corresponding rotatable members and provide 115 longitudinal ribs 49 on the inner surface of the vat 47, which peripherally engage the discs 20 and serve as supports therefor, thus taking that much weight off the main drive-shaft 5 and relieving the shaft of wear in a 120 corresponding degree.

The various grooved lapping plates 1, 2, 3, and 4 are preferably formed in sections, as is indicated in Fig. 3 of the drawings, and are clamped into place on the faces of the supporting members by means of the holding members 50 which, by means of the screws 51, clamp the plates against the shoulders 52 formed on each plate-carrying member near the central portion thereof. 130

It will be seen that the operation of the ball-lapping device described is continuous and that the balls, when they have traversed any given groove in the stationary plate 5 under the impelling action of the contiguous rotating plate, are automatically transferred to the next groove in the series and are also transferred from one set of grinding members to the next when the balls have traversed 10 in succession all the grooves in a set, so that, under normal operating conditions, the balls are mechanically transferred from groove to groove and from lapping unit to lapping unit in succession and without any 15 interruption of the lapping operation.

What I claim is—

1. A ball-lapping machine comprising: a plurality of sets of relatively-rotatable members having lapping grooves along which 20 the balls are impelled by the relative rotation of said members, means for transferring the balls from groove to groove in each set, and means for transferring the balls from one set of relatively-rotatable members to 25 another.

2. A ball-lapping machine comprising: a plurality of lapping units through which the balls are passed in a lapping operation, means for transferring the balls from one 30 lapping unit to another as the passage of the balls through each unit is completed, and means whereby the number of lapping units employed may be increased or diminished to suit the requirements of the work.

3. A ball-lapping machine comprising: a plurality of sets of relatively-rotatable members having lapping grooves along which the balls are impelled by the relative rotation of said members, means for automatically transferring the balls from groove to groove in each set in succession, and means for automatically transferring the balls to another set of relatively-rotatable members upon the completion of travel of 40 the balls through the grooves of one of the sets.

4. A ball-lapping machine comprising: a plurality of sets of relatively-rotatable members having lapping grooves along which 50 the balls are impelled by the relative rotation of said members, means for transferring the balls from groove to groove in each set, means for transferring the balls from one set of relatively-rotatable members to another, and means whereby the number of sets of lapping members employed may be increased or diminished to suit the requirements of the work.

5. A ball-lapping machine comprising: a 60 plurality of sets of relatively-rotatable members having lapping grooves along which the balls are impelled by the relative rotation of said members, means for automatically transferring the balls from groove 65 to groove in each set in succession and in

a certain order, means for automatically transferring the balls to another set of relatively-rotatable members upon the completion of travel of the balls through the grooves of one set, and means for holding 70 a mass of liquid abrasive material in such relation to the rotatable members that the members are partially immersed therein, whereby the rotation of said members stirs the material and applies it to the lapping 75 grooves.

6. A ball-lapping machine comprising: relatively-rotatable members mounted on a horizontal axis and having lapping grooves along which the balls are impelled 80 by the relative rotation of said members, and a container for abrasive material on which said members are mounted in such manner that the lower portions of said members are immersed in said material, 85 whereby the operation of said members stirs the material and applies it to the lapping grooves.

7. A ball-lapping machine comprising: relatively-rotatable members having lapping grooves along which the balls are impelled by the relative rotation of said members, the successive grooves traversed by the balls being formed with a progressive decrease in size, whereby a constant size relation is maintained between the balls and 95 the lapping grooves.

8. A ball-lapping machine comprising: relatively-rotatable members having lapping grooves along which the balls are impelled by the relative rotation of said members, means for automatically transferring the balls from groove to groove in succession and in a certain order, and said successive grooves being formed with a progressive decrease in size, whereby a constant size relation is maintained between the ball and the lapping grooves.

9. A ball-lapping machine comprising: a plurality of sets of relatively-rotatable 110 members having lapping grooves along which the balls are impelled by the relative rotation of said members, means for automatically transferring the balls from groove to groove in each set in succession and in a certain order, and means for automatically transferring the balls to another set of relatively-rotatable members upon the completion of travel of the balls through the grooves of one set, said lapping grooves 115 being formed with a progressive decrease in size, whereby a constant size relation is maintained between the balls and the lapping grooves as the balls travel through the machine and each groove invariably 120 operates on balls of substantially the same size.

10. A ball-lapping machine comprising: a plurality of sets of relatively-rotatable members having lapping grooves along 130

- which the balls are impelled by the relative rotation of said members, means for automatically transferring the balls from groove to groove in each set in succession, 5 and means for automatically transferring the balls to another set of relatively-rotatable members upon the completion of travel of the balls through the grooves of one set, the number of sets of lapping members 10 being approximately sufficient to complete the lapping of the balls in a single journey through the machine, whereby each lapping groove acts on balls of substantially the same size.
15. 11. A ball-lapping machine comprising: relatively-rotatable members having lapping grooves along which the balls are impelled by the relative rotation of said members, said lapping grooves being separated by 20 partition walls whose width is such that the rate of wear on the faces of said partition walls is greater than the wear on the surfaces of the grooves, whereby an effective operating pressure and size relation between the balls and the grooves is 25 constantly maintained.

12. A ball-lapping machine comprising: relatively-rotatable lapping members, a horizontal shaft on which said members are 30 mounted, said members being mounted to be moved longitudinally of said axis, a collar adjustably mounted on said shaft for pressing said members into close operating relation, and a collar rigidly secured to said 35 shaft and serving as an abutment member against which said lapping members are pressed, whereby the bearings in which said shaft is journaled are relieved of end thrust, said lapping members being removably 40 mounted on the shaft to provide for varying the number of members used.

13. A ball-lapping machine comprising: relatively-rotatable lapping members, a horizontal shaft on which said members are 45 mounted, said members being mounted to be moved longitudinally of said shaft, a collar having threaded engagement with said shaft for pressing said members into effective operative relation, a spring interposed between 50 said collar and said lapping members, a collar rigidly secured to said shaft and serving as an abutment member against which said lapping members are pressed, whereby the bearings in which said shaft is mounted 55 are relieved of end thrust, and said lapping members being individually removable at will from said shaft to vary the number of members used, said shaft being threaded for a substantial part of its length to adjust 60 the position of the movable collar to the number of members used.

14. A ball-lapping device comprising: a lapping member having oppositely-disposed faces with lapping grooves formed in said 65 faces, means for impelling balls along said

grooves to perform the lapping operation, and means for transferring the balls from a groove in one face of the lapping member to a groove in the opposite face in alternation as the travel of the balls through each 70 individual groove is completed.

15. A ball-lapping device comprising: a lapping member having oppositely-disposed faces with concentrically-arranged lapping grooves formed in said faces, means for impelling balls along said grooves to perform the lapping operation, and means for transferring the balls from a groove in one face of the lapping member to a groove in the 75 opposite face in alternation and in succession from the innermost to the outermost groove, as the travel of the balls through the individual grooves is completed.

16. A ball-lapping device comprising: a lapping plate having oppositely-disposed lapping faces, lapping plates arranged in cooperative relation with said faces, concentric ball-lapping grooves formed in the contiguous faces of said plates, means for relatively rotating said plates to impel the balls 80 through said grooves, and means for transferring the balls from a groove in one face of the intermediate lapping plate through said plate to a groove in the opposite face thereof in alternation and in succession from 85 the innermost to the outermost groove as the travel of the balls through the individual grooves is completed.

17. A ball-lapping device comprising: a lapping plate having oppositely-disposed 90 lapping faces, lapping plates arranged in cooperative relation with said faces, concentric ball-lapping grooves formed in oppositely-disposed pairs in the contiguous faces 95 of said plates, means for relatively rotating said plates to impel the balls through said 100 grooves, and means for transferring the balls from a groove in one face of the intermediate lapping member to the oppositely-disposed groove of the pair and from the second 105 groove of the pair to the opposite face of the intermediate lapping member and the first groove of the next outer pair of grooves.

18. A ball-lapping machine comprising: a stationary lapping member, a rotatable lapping member arranged to rotate substantially in contact with said stationary member, a plurality of concentric grooves in the contacting surface of one of said members so arranged that balls placed in said grooves 110 will be caused to travel therein by the rotation of said rotatable member, and transfer passages in said stationary lapping member for transferring the balls from one to another of said concentric grooves when the 115 travel of the balls about the path of travel afforded by each groove has been substantially completed.

19. A ball-lapping machine comprising: a stationary lapping member having oppo- 120

- sitely-disposed lapping surfaces, rotatable lapping members arranged to rotate substantially in contact with the oppositely-disposed lapping surfaces of the interposed stationary 5 lapping member, a plurality of annular grooves in each set of contacting surfaces so arranged that balls placed in said grooves will be caused to travel therein by the rotation of said rotatable members, and transfer 10 passages in said stationary member for transferring the balls from a groove in one set of contact surfaces to a groove in the other set when the travel of the balls about the path of travel afforded by the first-named 15 groove has been substantially completed.
20. A ball-lapping machine comprising: a stationary lapping member having oppositely-disposed lapping surfaces, rotatable lapping members arranged to rotate substantially in contact with the oppositely-disposed lapping surfaces of the interposed stationary lapping member, a plurality of concentric grooves in each set of contacting surfaces with a groove in each set oppositely disposed with relation to a corresponding groove in the other set, said grooves being so arranged that balls placed therein will be caused to travel in said grooves by the rotation of said rotatable members, and 25 transfer passages in said stationary member for transferring the balls from a groove in one set of contact surfaces to the oppositely-disposed groove in the other set when the travel of the balls about the path of travel 30 afforded by the first-named groove has been substantially completed.
21. A ball-lapping machine comprising: a stationary lapping member having oppositely-disposed lapping surfaces, rotatable 40 lapping members arranged to rotate substantially in contact with the oppositely-disposed lapping surfaces of the interposed stationary lapping member, a plurality of concentric grooves in each set of contacting surfaces with a groove in each set oppositely disposed with relation to a corresponding groove in the other set, said grooves being so arranged that balls placed therein will be caused to travel in said grooves by the 45 rotation of said rotatable members, transfer passages in said stationary member for transferring the balls from a groove in one set of contact surfaces to the oppositely-disposed groove in the other set when the 50 travel of the balls about through the first-named groove has been completed, and other transfer passages in said stationary member for re-transferring the balls from the second-named groove to a groove in the 55 first-named set radially removed from the first-named groove.
22. A ball-lapping machine comprising: a plurality of sets of lapping devices, each set consisting of a stationary lapping member having oppositely-disposed lapping surfaces, rotatable lapping members arranged to rotate substantially in contact with the oppositely-disposed lapping surfaces of the interposed stationary lapping member, a plurality of annular grooves in each set of 60 contact surfaces, transfer passages in said stationary member for transferring balls successively from one to another of said grooves until all the grooves have been traversed by the balls, means for feeding balls to the first set of lapping devices, and means for automatically conveying balls from one to another set of lapping devices as the balls 65 complete their travel through the series of grooves in each set, whereby the lapping operation is rendered continuous.
23. A ball-lapping machine comprising: a substantially disc-shaped stationary lapping member having oppositely-disposed lapping surfaces, substantially disc-shaped 70 rotatable lapping members arranged to rotate substantially in contact with the oppositely-disposed lapping surfaces of the interposed stationary lapping member, said lapping members being mounted on a horizontal axis, a container for abrasive material into which the lower portions of said lapping members extend, a plurality of annular grooves in each set of contact surfaces, and transfer passages in said stationary 75 member for transferring balls successively from one to another of said grooves.
24. A ball-lapping machine comprising: a plurality of sets of lapping devices, each set consisting of a substantially disc-shaped 80 stationary lapping member having oppositely-disposed lapping surfaces, substantially disc-shaped rotatable lapping members arranged to rotate substantially in contact with the oppositely-disposed lapping surfaces of the interposed stationary lapping members, said lapping members being mounted on a horizontal axis, a container for abrasive material into which the lower 85 portions of said lapping members extend, a plurality of annular grooves in each set of contact surfaces, transfer passages in each stationary member for transferring balls successively from one to another of said grooves until all the grooves have been traversed by the balls, means including a spring for pressing the lapping members into effective ball-lapping relation, means for continuously feeding balls to the first set of the plurality of lapping devices, and means for automatically conveying the balls from one lapping set to another as the balls 90 complete their travel through the series of grooves in each set, whereby the operation of lapping the balls is rendered continuous.

ALBERT F. ROCKWELL.
